(57) **CLAIM**

The ornamental design for a storage case for video games, as shown and described.

DESCRIPTION

FIG. 1 is a front perspective view of a storage case for video games showing my new design, the large broken lines representing access zippers;

FIG. 2 is a right elevation view of the invention illustrated in FIG. 1;

FIG. 3 is a bottom plan view of the invention illustrated in FIG. 1;

FIG. 4 is a left elevation view of the invention illustrated in FIG. 1;

FIG. 5 is a top plan view of the invention illustrated in FIG. 1 with the carrying strap deflected to reveal the upper portion of the invention;

FIG. 6 is a front elevation view of the invention illustrated in FIG. 1; and,

FIG. 7 is a rear elevation view of the invention illustrated in FIG. 1.
